CIGARETTE CASE

William Alexander Dion, Plainville, Mass., assignor to Evans Case Company, North Attleboro, Mass., a corporation of Massachusetts

Application April 10, 1930, Serial No. 443,171

8 Claims. (Cl. 206—41)

This invention relates to cases such as are adapted to hold cigarettes or other small articles and particularly to combined cigarette cases and lighters.

5 One of the objects of the invention is to provide a simple and compact device of this character which is convenient in use and may be economically produced.

Another object is to provide a simple and effective spring arrangement by means of which various parts of the case may be relatively moved or urged.

Other objects will be in part obvious and in part pointed out hereinafter.

15 The invention accordingly consists in the features of construction, combinations of elements, and arrangements of parts as will be exemplified in the structure to be hereinafter described and the scope of the application of which will be indicated in the following claims.

In the accompanying drawing, in which are shown the features of a selected embodiment of the invention:

20 Fig. 1 is a side elevation with the case in open position;

Fig. 2 is a section on the line 2—2 of Fig. 1;

Fig. 3 is an enlarged detail view;

Fig. 4 is a section on the line 4—4 of Fig. 3;

30 Fig. 5 is an elevation of a modified form of case, the parts being in open position, and

Fig. 6 is an enlarged detail view of a portion of the device shown in Fig. 5.

Referring to the drawing and particularly to Figs. 1 to 4 inclusive, the device shown is a combination cigarette case and lighter. The case 10 comprises two relatively movable sections 11 and 12 which are connected by a hinge pin as 13 along one margin thereof. At one end of the section 11 is provided a fuel tank 14. A wick as 15 extends through the end wall 16 of the casing and projects into the interior of the tank 14. On this wall 16 adjacent the projecting extremity of the wick, is provided a suitable sparking mechanism as 17. As this sparking mechanism per se forms no part of the present invention and as any suitable mechanism for this purpose might be used, it is not believed that any detail description thereof is necessary.

In the wall 16 of the casing may be provided a 50 filling opening 18 which in the present instance is punched through the wall in any convenient manner and an interiorly threaded bushing or lining as 19 is driven therein. At the outer end of this bushing is provided an outwardly extending 55 flange 20 which overlies the casing wall and may

be secured thereto by solder or other suitable means, if deemed expedient. A closure plug as 21 fits within the bore of the bushing 19 and is provided at its outer end with a head as 22 which is adapted to be brought firmly in contact with the flange 20 of the bushing to form a tight joint at this point. A suitable gasket as 23 may be interposed therebetween for this purpose. In the bottom face of this plug 21 may be inserted a holder 5 as 24 for sparking metal as is customary in devices of this character. A capped opening as at 25 is provided to permit sparking material to be supplied to the mechanism 17.

Near the hinge connection 13 there is attached to the marginal portion of the section 12 of the case, a plate as 35 from which project a pair of lugs 36 each having its outer end portion looped about a hinge pin 37 which is supported thereby near its ends. The hinge pin 37 is parallel with the pin 13 and spaced therefrom. Pivots 10 mounted upon this pin 37 is a presser member 38 which is adapted to coact with the inner face 15 of the section 12 to retain cigarettes as 39 in position within this section. A coil spring as 40 is wound about the pivot pin 13 in one direction 20 and then about the pivot pin 37 in the opposite direction. One end 41 of this spring may be tied to the section 11 of the case by being passed through a perforation as 42 in the marginal portion thereof. Similarly the opposite end 43 of 25 this spring may be secured to the presser member 38 by being passed through a perforation as 44 therein. This spring acts to yieldingly retain the sections in closed position and also to cause the 30 presser member 38 to coact with the section 12 for the purpose described.

When the case is opened against the action of the spring 40, this causes the portion of this spring about the pivot pin 13 to be wound more tightly 40 around this pin and to slightly draw over the connecting portion 45 of the spring, thus tightening the portion of the spring about the pivot pin 37 and increasing the pressure of the member 38 on the cigarettes thereunder. The opening of the case in the manner described also acts to cause 45 the portion 45 of the spring to be wound somewhat further about the pivot pin 13. In the same manner the drawing of the presser member away from the cigarettes in the section 12 or the wall 50 against which such presser member acts, tends to increase the tension on the spring about the pin 13 and thus the action of the same to close the case. Instead of acting to close the case in the manner described, it will be evident that the same 55 spring arrangement may be used to assist the

opening of such case by reversing the winding about the pin 13.

Referring to Figs. 5 and 6, there is shown a simple type of cigarette case 50 in which the sections 51 and 52 are hingedly connected by a pin 53 in substantially the same manner as in the embodiment already described. A spring 54 is wrapped about this pivot and the pivot pin 55 on which is mounted the presser member 56. One end 57 of this spring is inserted through an opening 58 in the presser member 56 and bent over beneath this member while the opposite extremity 59 of the spring passes through an opening 60 in the marginal portion of the section 51. This spring 54 is wound in opposite directions about the pivot pins 53 and 55 as in the previous embodiment and the action is the same as there described.

It will readily be evident that this same spring construction is applicable to cases for a wide variety of purposes where a double spring action is required. The device is simple and compact and may be economically produced. In the lighter construction the form of filling opening shown very materially reduces the cost of producing the lighter as no threading of the walls of the tank is necessary and the parts may be quickly and easily assembled.

It will be seen that there is provided a construction of an essentially practical nature in which the several objects of this invention are attained.

As many possible embodiments may be made of the above invention without departing from the scope thereof, it is to be understood that all matter herein set forth or shown in the accompanying drawing is to be interpreted as illustrative and not in a limiting sense.

I claim:

- 40 1. A case comprising a pair of relatively movable sections, a hinge pin connecting said sections at one margin thereof, oppositely disposed lugs mounted on one of said sections and projecting therefrom, a second hinge pin mounted in said lugs in substantially parallel relation with the first hinge pin and spaced therefrom, a presser member mounted on the second hinge pin, and a coil spring wound around said pins in opposite directions and coacting with said sections and said member to yieldingly maintain said sections in closed position and said member pressed toward one of said sections, the opening of said case acting to increase the pressure of said member.
- 55 2. A case comprising a pair of relatively movable sections, a hinge pin connecting said sections at one margin thereof, oppositely disposed lugs mounted on one of said sections and projecting therefrom, a second hinge pin mounted in said lugs in substantially parallel relation with the first hinge pin and spaced therefrom, a presser member mounted on the second hinge pin and coacting with one of said sections, and a coil spring wound around said pins in opposite directions and coacting with said sections and said member to yieldingly maintain said sections in closed position and said member pressed toward the section with which it coacts, movement of said member from the section acting to increase the closing action of said spring.
- 70 3. In a cigarette case, in combination, a container comprised of a pair of casings, one of said casings comprising a cover for said container, hinge means connecting said casings, a presser

pivotedly mounted with respect to said casings, and adjacent said hinge means, and a coil spring related to said hinge means and having opposite windings to urge said presser against one of said casings and reacting against both of said casings 5 to urge them together.

4. In a cigarette case, in combination, a container comprising a pair of relatively movable sections, a hinge pin connecting said sections substantially at one margin thereof, a presser 10 pivotally mounted upon said sections, and spring means having opposite windings, one winding being connected to said presser to urge said presser outwardly against one of said sections and the other of said windings being connected to said 15 sections to urge said sections toward each other, said spring means being adapted to ease up on said presser member as said sections are moved toward each other.

5. In a cigarette case, in combination, a container comprising a pair of relatively movable cover members, a hinge pin connecting said cover members, a presser member pivotally connected to said container adjacent said hinge pin, spring means comprising two coacting sections, 25 one of said sections being adapted to resiliently force said cover members toward each other and the other of said sections being adapted to resiliently force said presser member against one of said cover members, said sections being so connected as to ease up on said presser member as said cover members are moved toward each other. 30

6. In a cigarette case, in combination, a container comprising a pair of relatively movable cover members, a hinge pin pivotally connecting 35 said cover members, a presser member hingedly mounted adjacent said hinge pin, and a pair of coacting coil springs connected to each other at one end, one of said springs being connected to said cover members to resiliently force said cover members toward each other and the other of said springs being connected to said presser member to resiliently hold said presser member against one of said cover members. 40

7. In a cigarette case, in combination, a container comprising a pair of relatively movable cover members, a pin pivotally connecting said cover members, a presser member, a pin pivotally connecting said presser member with one of said members, spring means comprising two sections 50 and having opposite windings one upon said pivot pin of said cover members and one upon said pivot pin of said presser member, said spring means adapted to force said cover members toward each other and said presser against one of said cover members, the closing of said sections adapted to diminish the pressure of said presser member against said cover member. 55

8. In a cigarette case, in combination, a pair of casings shaped to rest in juxtaposed relationship to form a case, a hinge connecting said casings so that they may pivot to an extended position, a presser, a pivotal mounting for said presser adjacent said hinge, and a single spring associated with said hinge and said mounting, 60 having a section pressing against said presser to urge said presser against one of said casings and having another section pressing against the other of said casings, whereby said casings are constantly urged into an extended position and said presser is constantly urged against one of said casings. 70
